DESIGN FOR A SPINAL PUNCTURE NEEDLE

Julius Brandenburg, New York, N. Y., assignor to
Brandenburg Instrument Co., Inc., a corpora-
tion of New York

Application June 10, 1944, Serial No. 113,939

Term of patent 7 years

(Cl. D83—1)

To all whom it may concern:

Be it known that I, Julius Brandenburg, a citizen of Hungary and a resident of the city of New York, in the county of New York and State of New York, have invented a new, original, and ornamental Design for a Spinal Puncture Needle, of which the following is a specification, reference being had to the accompanying drawing, forming a part thereof.

Fig. 1 is a side view of a spinal puncture needle showing my new design; and

Fig. 2 is a front view thereof.

I claim:

The ornamental design for a spinal puncture needle, substantially as shown.

JULIUS BRANDENBURG.
